ATTORNEY

UNITED STATES PATENT OFFICE

2,204,571

VOLTAGE REGULATION SYSTEM FOR
VACUUM TUBE AMPLIFIERSJohn F. Byrne, Cedar Rapids, Iowa, assignor to
Collins Radio Company, Cedar Rapids, Iowa, a
corporation of Iowa

Application April 21, 1938, Serial No. 203,435

7 Claims. (Cl. 179—171)

My invention relates broadly to electron tube amplification circuits and more particularly to a voltage regulation system therefor.

One of the objects of my invention is to provide an electron tube amplification circuit having voltage regulating means for maintaining substantially constant output voltage independently of load conditions.

Another object of my invention is to provide voltage regulating means controlled jointly from the input and the output circuits of an electron tube amplifier and operative to maintain substantially constant output voltage under load and open circuit conditions.

Still another object of my invention is to provide normally balanced circuit means in the input circuit of an electron tube amplifier operative to deliver a differential of voltage in the input circuit upon connection of a load in the output circuit of the amplifier to counteract for voltage variations in the output circuit due to the load current.

A further object of my invention is to provide a regulating transformer connected in the input circuit of an electron tube amplifier for voltage control, and having the primary winding thereof energized by components of the input and output voltages in phase opposition under no load conditions, and the secondary winding thereof adapted to deliver a voltage proportional to the differential of the primary voltages under load conditions for regulating the operation of the amplifier.

A still further object of my invention is to provide an electron tube amplifier having voltage regulating means operative in the input grid circuit auxiliary to the signal input for producing constant voltage conditions in the output circuit.

Other and further objects of my invention reside in the system and circuit arrangements hereinafter more fully described with reference to the accompanying drawing, in which:

Figure 1 is a schematic diagram illustrating the essential factors in the voltage regulating system for electron tube amplifiers of my invention; and Fig. 2 is a schematic diagram of a modified form of electron tube amplifier embodying the voltage regulation system of my invention.

My invention deals with a system of voltage regulation, as applied to a vacuum tube amplifier which operates into a load of variable impedance characteristic. This type of amplifier operation is encountered when the amplifier is followed in cascade by an amplifier of the "Class

B" type, which requires driving power not proportional to the square of the input voltage.

The system as illustrated in Fig. 1 in schematic form includes an electron tube 1 provided with anode 1a, grid 1g, and cathode 1c. An output transformer 2 comprises conventional primary and secondary windings 2a and 2b, respectively, and an auxiliary winding 2c in the nature of a secondary of an auto-transformer arrangement employing the same primary winding 2a as the conventional arrangement. The input source of energy is schematically indicated at 3, and the regulating transformer is shown at 4, with primary 4a and secondary 4b wound on a magnetic core. Suitable sources of bias potential 5 and power are represented by batteries at 6 in the grid circuit and at 7 in the anode circuit; any desired potential sources may be employed in lieu of the batteries.

The grid circuit comprises the secondary 4b of the regulating transformer 4, input source 3, and the source of bias potential 6 connected in series between grid 1g and cathode 1c. The primary 4a of the regulating transformer is energized by the series circuit including the input source 3, battery sources 6 and 7, the secondary winding 2c and a blocking condenser 5 which prevents the flow of direct current from the sources 6 and 7. The alternating potentials E_1 and E_m of the input source 3 and the secondary 2c respectively, are connected in phase opposition under no load conditions in the output circuit, so that the magnetic fields in the regulating transformer 4 are balanced. The effective grid voltage is designated E_g , and the output voltage E_o . In operation, this output voltage E_o is not materially affected by load demands, due to the functioning of the voltage regulating system of my invention.

With the grid voltage applied, the amplified voltage E_o appears in the output circuit, and simultaneously the voltage E_m is induced in the auxiliary winding 2c of the output transformer 2. The value of this voltage is such that it is equal to and substantially in phase opposition with the grid voltage E_g when no load is in the output circuit. Under these conditions, the voltage appearing across the primary 4a of the magnetic core regulating transformer 4 is zero. When a load is connected in the output circuit, the output voltage E_o tends to decrease; at the same time, the monitoring voltage E_m tends to decrease, and in so doing, the difference between the grid voltage E_g and the monitoring voltage E_m appears across the transformer 4. This

transformer is so phased that the grid voltage E_g is increased, and the decrease in output voltage due to load is greatly reduced. The amount of stabilization of the output voltage will depend upon the turns ratio of the regulating transformer 4, the greater the turns ratio, the greater the stabilization.

Fig. 2 shows schematically a modified form of my invention operative in the same manner as that illustrated in Fig. 1. In the output circuit in lieu of an auxiliary winding 2c I provide a voltage divider at 8, connected in parallel with the primary 2a of the output transformer 2. The monitoring voltage E_m is derived from a portion 10 of the voltage divider by a tap connection 9 leading to the primary 4a' of the regulating transformer 4', through blocking condenser 5'. The circuit of the primary 4a' is completed in the input of the amplifier through a separate source of 15 input energy 3'', the voltage of which, as indicated, is equal to the voltage of the main input source 3' connected in the grid circuit. The secondary 4b' of the regulating transformer 4' is connected with the source 3' and bias potential 20 source 6 across the grid-cathode path of the tube 1, as in Fig. 1.

The principal difference, therefore, in the circuits of Figs. 1 and 2 is in the primary circuit of the regulating transformer 4, that in Fig. 1 including the same input source 3 as is connected in the grid circuit, with one side of the source connected with both primary and secondary windings. Thus, the primary 4a is energized by the voltages E_1 and E_m , and the secondary 4b is responsive simultaneously to the differential of both voltages, through the transformer, and to the voltage E_1 of the signal input directly from the source 3. In Fig. 2, the regulating transformer 4' has independent primary and secondary circuits, made possible by the provision of the separate input source 3''. The voltage E_g between grid and cathode is the same as that in the circuit of Fig. 1, but the main input source 3' is relieved of such reaction as may be found in the source 3, Fig. 1, 35 due to the effect of the currents in the primary 4a of the transformer 4. In the circuit of Fig. 2, such reactions are confined to the separate source 3'', and the operation of the amplifier is preserved subject to the signal input voltage, with 40 the regulatory voltage simultaneously effective, 45 for delivering the amplified signal in proper form.

A unique feature of the regulator is that the turns ratio of the transformer 4 may be increased indefinitely without causing oscillation in the system. It may be demonstrated mathematically 50 that the A. C. plate resistance of the amplifier tube is reduced by a factor

$$\frac{1}{1+a}$$

60 where a is the turns ratio of the regulator transformer. For example, a class "A" audio amplifier employing a type 845 tube, with a regulator transformer having a turns ratio of 5:1, would have the following apparent characteristics:

65 Voltage gain, no load=5
Apparent plate resistance=

$$\frac{1800}{1+5}=300 \text{ ohms}$$

70 The amplifier stage, considered as a generator, has an internal impedance only one sixth of that of the unregulated amplifier.

75 It is seen that as the turns ratio of the transformer is increased, the apparent resistance of the amplifier tends toward zero. It should also

be noted that it never becomes negative, which indicates that no oscillation can take place for high turns ratios.

I have disclosed my invention in certain preferred embodiments, but I desire it to be understood that further modifications may be made, and that I intend no limitations upon my invention except as are imposed by the scope of the appended claims.

What I claim as new and desire to secure by 10 Letters Patent of the United States is as follows:

1. An electron tube amplifier comprising an electron tube having anode, grid and cathode electrodes; an anode circuit including output means and a source of power connected between 15 said anode and said cathode; a grid circuit including a transformer secondary winding, input means, and a source of bias potential connected between said grid and said cathode; a transformer primary winding coupled with said secondary 20 winding; and a series circuit including said primary winding, a direct current blocking condenser, means for deriving a voltage from said output means, said sources of power and bias potential, and means for deriving a voltage from said input 25 means; said voltages derived from said input and said output means being connected in phase opposition under no load conditions in said output circuit, and said secondary winding being connected so that voltage thereacross is effective to 30 counteract voltage variations in said output circuit under load conditions for substantially reducing said variations and the voltage in said secondary winding.

2. An electron tube amplifier comprising an electron tube having anode, grid and cathode electrodes; an anode circuit including output means and a source of power connected between 35 said anode and said cathode, said output means comprising a primary winding constituting an 40 autotransformer having a tap connection therefrom connected with said source of power, and a secondary winding coupled with said primary winding for connection to a load; a regulating transformer having primary and secondary sections; a series circuit including said secondary section, input means, and a source of bias potential connected between said grid and said cathode; and a series circuit including the primary section 45 of said regulating transformer, said input means, 50 said sources of bias potential and power, said tap connection and a portion of the said primary winding separate from said anode circuit, and a blocking condenser; alternating voltages in the last said series circuit being connected in phase 55 opposition under no load conditions, and voltage in said secondary section of the regulating transformer in the first said series circuit under load conditions being effective through said electron tube to counteract voltage variations in said 60 output means.

3. An electron tube amplifier comprising an electron tube having anode, grid and cathode electrodes; an anode circuit including output means and a source of power connected between 65 said anode and said cathode; a voltage divider connected parallel to said output means and having a tap connection; a grid circuit including a transformer secondary winding, input means, and a source of bias potential connected between 70 said grid and said cathode; a transformer primary winding coupled with said secondary winding; and a series circuit including said primary winding, a direct current blocking condenser, said 75 tap connection and a portion of said voltage di-

vider, said sources of power and bias potential, and separate input means; alternating voltages in said series circuit being connected in phase opposition under no load conditions, and voltage 5 in said secondary winding under load conditions being effective to counteract voltage variations in said output means.

4. An electron tube amplifier as set forth in claim 1, wherein said means for deriving a voltage 10 from said output means comprises a portion of said output means separate from said anode circuit, said source of power being connected to said output means by a tap connection to define the said portion.

15 5. An electron tube amplifier as set forth in claim 1, wherein said means for deriving a voltage from said output means comprises a voltage

divider connected in parallel with said output means and a tap connection on said voltage divider connected with said primary winding through said blocking condenser.

6. An electron tube amplifier as set forth in 5 claim 1, wherein said means for deriving a voltage from said input means comprises connections to said input means parallel to the connection thereof in said grid circuit.

7. An electron tube amplifier as set forth in 10 claim 1, wherein said means for deriving a voltage from said input means comprises a separate device coupled with the input means and independent of the connection thereof in said grid circuit.
